SYSTEM FOR REPRODUCING SOUND FROM
A SOUND RECORD

John Hays Hammond, Jr., Gloucester, Mass.

Application August 21, 1931, Serial No. 553,502
Renewed September 14, 1933

30 Claims. (Cl. 179—100.4)

This invention relates to the production of sound from sound records, and more particularly to an improved method and system for controlling the amount of sound in accordance with the characteristics of the energy derived from the record.

The invention provides for controlling the sound production so that undesired sounds, such as those due to ground noise and needle scratch are not produced unless accompanied by desired sounds such as those due to speech and music, which mask the presence of the undesired sounds.

The system comprises a signal amplifier which receives energy from a sound record and applies the same after amplification to a suitable sound producing device, such as a loud speaker. A control device is also utilized which is actuated in accordance with the original record and controls the amplification characteristics of the signal amplifier. By this means a variable amplification characteristic is obtained by which strong signals are amplified to a greater extent than weak signals. The present invention relates particularly to the manner in which the control is exercised, and achieves new and useful results as regards smoothness of operation, speed of action, the degree of perfection in elimination and masking of undesired sounds, and in other respects.

The characteristics of the control device are such that weak signal currents outside the ground noise and scratch frequency range cause a relatively great change in the amplification of the signal amplifier, while weak currents in the ground noise and scratch frequency range produce little or no change. For stronger currents the control is not relatively so great nor is there so great distinction as to what frequencies may exercise the control. Initial operating conditions of the signal amplifier are such that it passes practically no current whatsoever. Because of the discrimination against scratch and ground noise currents by the control device, these currents do not render the signal amplifier operative, but the desired signals render the amplifier operative and cause the same to amplify the currents produced by the sound record by a variable amount which is determined by the frequency and amplitude characteristics of said currents.

For this purpose the control device includes two or more control channels which are adapted to exert different influences on the signal amplifier. In particular two such control channels may be employed, the first capable of producing relatively great change of signal amplifier performance, and the second capable of producing

relatively small change. The first and potentially stronger channel, however, is arranged with frequency characteristics to discriminate against control of the signal amplifier by currents of scratch or ground noise frequencies, and further is arranged so that its control action on strong signals is limited. The second or relatively weaker control channel, which does not necessarily discriminate against currents of scratch or ground noise frequencies, does not contribute appreciably to the control on weak signals, but predominates over the first channel after limiting action has prevented the first channel from exercising further control.

By suitable adjustment of the frequency discrimination characteristics of the potentially stronger control channel, and by suitably limiting the action of each potentially stronger channel prior to any limiting action on a weaker channel, a suitable control arrangement of the signal amplifier is produced which is automatically variable both on a frequency basis and signal strength basis. As a result, high frequency currents of the scratch and ground noise frequency range occurring in the input to the signal amplifier produce little or no output sound energy unless they include currents due to relatively strong desired signal tones, or are accompanied by lower frequency energy, the presence of either of which in the sound output masks the presence of the undesired noises.

Although the novel features which are characteristic of this invention will be particularly pointed out in the claims appended hereto, the invention itself as to its objects and advantages, the mode of its operation, and the manner of its organization may be better understood by referring to the following description taken in connection with the accompanying drawings forming a part thereof, in which

Fig. 1 illustrates diagrammatically the system as applied to the reproduction of a sound record of a talking moving picture projector or a phonograph;

Fig. 2 is a series of curves showing characteristics of part of the amplifier at one operating frequency.

Fig. 3 is a diagrammatic representation of a modified form of the invention.

In the following description and in the claims, parts will be identified by specific names for convenience, but they are intended to be as generic in their application to similar parts as the art will permit.

Like reference characters denote like parts in the several figures of the drawings.

Referring to the accompanying drawings and particularly to Fig. 1, a source of electrical energy is provided at the primary of transformer 21, from sound on film or sound on disc in accordance with the setting of a switch 17. For producing electrical energy from sound on disc, there is provided a phonograph pickup device 18. For producing electrical energy from sound on film, there is provided a light source 10, from which light traverses lens 11, and after passing through aperture 12 of aperture plate 13 impinges upon the moving sound track of film 14. The light transmitted through the sound track and varied in accordance with the record thereon, impinges on a photo-electric cell 15, which is connected in circuit with a battery and the primary of transformer 16. The secondary of transformer 16 is connected to two terminals of switch 17, and the pickup 18 is connected to two other terminals of said switch in such a manner that energy from either source may be connected to the primary of transformer 21. The parts so far described are typical of any source of electrical tone input to the transformer 21.

The signal amplifier comprises a first stage of amplification including tube 22 which is coupled by a transformer 51 to a second stage of amplification including tubes 53 connected in push-pull relationship. The output of said tubes 53 is coupled by transformer 54 to a loud speaking device 55, for example of the dynamic type having a field coil 56. A resistance 52 is connected across the primary of transformer 51 and serves as an equalizing impedance.

The output of transformer 21 is connected to the input circuit of tube 22, the grid return including resistances 23 and 24, battery 43 and potentiometer 43a. There is accordingly provided a grid bias composed of the fixed bias due to battery 43; a manually adjusted bias due to potentiometer 43a and an automatically variable bias due to the potential drop caused by currents passing through resistances 23 and 24.

The complete control channel includes an amplifier 27 to which energy is applied from the secondary of transformer 21 through coupling condenser 21a. The output circuit of said amplifier includes a transformer 34 by which energy is transferred to a rectifier circuit including rectifier 35 and resistances 36 and 23. The control channel also includes an amplifier 28 which is coupled to the output circuit of amplifier 27 through coupling condenser 28a and has included in its output circuit a transformer 31 which transfers energy through a filter network 38 and transformer 39 to a rectifier circuit including rectifier 41 and resistances 42 and 24. The filter network is preferably so designed as to discriminate against high frequency tones, such as the undesirable tones, above-mentioned.

A limiting device including tube 48 is connected across resistance 24 and is adjustable by means of adjustable tap 46 on potentiometer 44 which is connected across battery 43, the adjustment being such as to limit the voltage drop across resistance 24 to a predetermined value. A limiting device such as tube 47 is also connected across resistances 23 and 24 and is controlled by adjustable tap 45 of potentiometer 44 to limit the voltage drop in said resistance and to prevent the bias change from exceeding a predetermined value.

All parts of the complete control channel which

contribute in determining the current through resistor 24 constitute the first or potentially stronger control channel, and all which contribute in determining the current through resistor 23 constitute the second or weaker control channel. Although some parts of the complete control channel are for simplicity common to both, such as amplifier 27, it is obvious that the two individual channels are substantially independent or could be made so to any desired degree.

In the operation of Fig. 1, battery 43 is so chosen and potentiometer 43a is so regulated that in the absence of signal, little or no plate current passes from the plate battery to the plate of tube 22. Under these conditions, the internal impedance of tube 22 is very high and for very weak signals the amplification of the stage including the device 22 is small or actually much less than unity so that the voltage to the grids of push-pull amplifier 53 may be even negligible compared with the voltage applied to the grid of device 22. In the absence of signal there may be a small current through resistances 23 and 24 due to energy from the filament heating devices of rectifier tubes 35 and 41. This initial current may be compensated for by the potentiometer adjustment above-mentioned.

When a signal is impressed upon device 22 a corresponding signal will simultaneously be impressed upon the control channel including devices 27 and 28. That part of the amplified energy output of device 27 which passes through transformer 34 is rectified by device 35 and the rectified output is smoothed out and delivered to resistance 23 causing a current to flow in the direction of the arrow. A small portion of the output energy of device 27 actuates device 28, the output of which traverses filter network 38 is rectified by device 41 and produces a current which flows in the direction of the arrow in the resistance 24. Consequently, the bias of tube 22 is decreased in accordance with the sum of the voltage drops in resistances 23 and 24, thereby lowering the internal impedance of the tube and permitting it to become more conductive.

By reason of the variable internal impedance of device 22, it is desirable to provide an equalizer impedance 52 across the input of transformer 51. This impedance serves to maintain the external output impedance of tube 22 substantially independent of the frequency, and the impedance of the devices connected to the primary of transformer 51 substantially independent of the internal impedance of the tube, whereby the fidelity of amplification is substantially the same regardless of the signal strength. Although a resistor type equalizer 52 has been shown for purposes of illustration, it is obvious that an impedance network of any desired type may be employed.

For weak input signals, the control on the performance of tube 22 is largely exercised by rectifier 41 which is supplied by transformer 37, since the output of tube 26 exceeds that of tube 27. Means is provided, however, for limiting the voltage drop across resistance 24 so that for higher signal strengths, the control channel including said resistance is prevented from exerting as much influence as the control channel including resistance 23.

For this purpose a limiter 48 is provided which operates to limit the output of rectifier 41 when the output voltage across resistance 24 exceeds a predetermined value. In the absence of cur-

rent through resistance 24, the plate of limiter 48 is negative with respect to the filament due to the bias impressed into the circuit by the setting of contact 46 on potentiometer 44.

5 Device 48 is accordingly non-conductive until the voltage drop across resistance 24 exceeds the bias voltage above-mentioned, after which the device 48 becomes conductive and prevents further voltage change across said resistance. 10 Resistance 42 assists in the limiting action and also operates as a part of the filter network for the output of rectifier 41.

The limiter 47 operates in accordance with the combined voltage drop across resistances 23 and 24 and is adjusted by means of contact 45 of potentiometer 44 to limit the voltage drop across said resistances in the manner similar to that pointed out in connection with limiter 48. Limiter 47 is preferably adjusted so that the combined voltage drop across resistances 23 and 24 will not reduce the grid bias of tube 22 below the value for which maximum undistorted signals may be obtained therefrom.

In general, the limiter 48 is adjusted to become operative at less signal strength than limiter 47, so that the relatively weaker control channel becomes the relatively stronger channel on strong signals.

It is seen then that by the use of two control channels, and a limiter on the potentially stronger channel, a quick action upon increase of signal is produced upon the amplifier control, with gradual tapered action as strong signals are used. The quick action at weak signals refers to rapid change of signal amplifier performance with change of input signal, by which small signals may change the signal amplifier from a non-operative to an operative condition. The quick action also refers to the rapidity with which the change of operation is brought about, due to the large amount of energy available for making the change. In both senses, the quick action is a desirable feature of the invention.

The action of the two control channels is depicted in Fig. 2, in which decrease of bias of the tube 22 due to the presence of the rectifier elements 41 and 35, is shown as dependent upon the input signal for a single frequency, say in the middle of the audible range. Curve "A" depicts the change of bias due to the first or potentially stronger control channel including the second stage amplifier device 23, rectifier 41, and limiter 48. Curve "B" depicts the change due to the second or relatively weaker control channel including the first stage amplifier device 27, rectifier 35 and limiter 47. Curve "C" depicts the total change of bias due to both control channels, and is seen to be characterized by a sharp decrease of bias for small signals, with gradual tapering effect, and finally no further decrease of bias at highest signals.

For a high frequency signal input, with the potentially stronger channel not operative due to action of filter 38, there would be no contribution to the change of bias due to curve "A", and curve "E" would coincide with "C" in depicting the total change of bias due to the entire control channel. For other frequencies for which filter 38 is only partially effective, the control curve would lie between curves "C" and "B" as here shown. It is to be understood that the nature of the control curves for different frequencies may be modified by adjustments of relative inputs to the first and second control amplifiers, by adjustment of the limiters, and by

adjustments of frequency characteristics of the two control channels so that a great variety of relations between gain ratio of the signal amplifier, and the wave form characteristics of the signals may be attained.

One such arrangement, for example, would proportion curve "C" such that substantially even decibel expansion would be obtained for all useful signal input values, with no frequency discrimination by the channels. Or another arrangement, for example, by making the weaker channel slightly more responsive to the high frequencies, as by adjustment of condenser 21, and of the characteristics of transformer 34 etc., would cause substantially equal output of the entire amplifier for all frequencies on high signal input, although the high frequencies are discriminated against on weak input. Or a third arrangement, as by removal of the limiter tube 48 or rendering it ineffective by adjustment of contact 46 would cause the signal amplifier to perform substantially as a normal amplifier with expansion only on very weak signals, and normal performance over a very wide range of signal inputs. This last-mentioned arrangement is useful for sound inputs with fairly marked difference of level between input stray noises, and lowest desired signal, for which complete ground noise elimination is desired without dynamic expansion of signal currents. All these arrangements are to be considered within the scope of the invention, or of structural modifications thereof.

A modification of the invention as applied in the control of a plurality of stages of a signal amplifier is shown in Fig. 3, in which the input may be from the terminals of switch 17, and the output circuit 59 may be connected to a loud-speaker, a telephone line, or a final high power stage (not shown). Across the input is a potentiometer 60, having adjustable taps 61 and 62 for controlling the distribution of energy to input transformers 21 of the signal amplifier and 71 of the control amplifier. The signal amplifier includes tube 22, coupling transformer 51, 45 push-pull amplifier tubes 53 and an output transformer 54, all similar to those described in connection with Fig. 1, except for the use of separate heater tubes.

Across the primary of transformer 51 is a resistance 63, and between plate and ground is a condenser 64 in series with a variable resistance 65. This network constitutes an impedance equalizer circuit, and also a tone control by which the frequency transmission characteristics of the signal amplifier may be adjusted. Equalizer resistances 66 are also provided for the windings of transformer 54. The grid and plate returns are bypassed to ground by suitable condensers, care being taken that the grid return bypass condensers are not of excessive capacity. The cathodes of tubes 53 are joined together, and grounded through an indicating milliammeter 67. The cathode of tube 22 is bypassed to ground. The operating plate potentials for the tubes, a potential for the cathode of tube 22, and heater currents are supplied in the usual manner from substantially fixed sources to be described later. The operating bias for the tubes, however, may be substantially fixed for normal amplifier operation, or may be made automatically variable. For this purpose the grid return of tube 22 is connected to one center terminal 69 of a double pole double throw switch 68; and the common grid return of tubes 53 is connected to the other center terminal 75

10. When this switch is thrown to right as shown in Fig. 3, the signal amplifier performs as a normal amplifier, with suitable fixed bias values. But when the switch is thrown to the left, the 5 signal amplifier performs as a controlled amplifier with grid bias supplied from the control circuits.

The control channel, operating from the input 10 transformer 71, includes first stage amplifier 72 with its output transformer 34, and second stage 15 amplifier 73 with its filter 38 and output transformer 39. One side of the secondaries of the 20 transformers 34 and 39 are connected to anodes of rectifiers 35 and 41 respectively, while the other 25 sides are joined together, and to conductor 74, which is at substantially fixed potential during 30 operation, and is bypassed to ground. In addition, voltage from the secondary of transformer 34 is fed to the grid of the second stage amplifier 73 by the use of coupling condenser 75 and 35 resistance 76. Suitable operating potentials for the 40 control amplifiers are supplied in the usual manner; in the present case resistances 77 and 78 being used to cut down the plate supply voltage.

The outputs of rectifiers 35 and 41 are fed to a 25 filtering, combining and distributing control network, including resistances 80, 81, 82, 83, 84, and a plurality of condensers. The output of rectifier 41 flows through resistances 83 and 84 to conductor 74, while the output of rectifier 35 flows 30 through resistors 80, 81, 82 and 84. Opposite sides of resistance 81 are connected to terminals 85 and 86 of switch 68, so that with switch 68 thrown to the left, the change of bias on tubes 35 due to rectifiers 35 and 41 is the voltage drop 35 in resistances 82 and 84, while the change of bias on tube 22 is the drop due to the drop in resistances 81, 82 and 84. An adjustable condenser bank 87 is provided for adjusting the timing to 40 make it slower, if desired than that provided by the various condensers of the grid return circuits. Limiter tubes 48 and 47 are provided to control the rectifier output, the anode of tube 48 being connected to the junction of resistances 82 and 84, and the anode of tube 47 being connected to terminal 85 of the switch 68.

The operating power for the tubes of the 50 entire circuit is supplied from power transformer 88, operating from an alternating current line. The secondary winding 89 supplies heater current to all tubes, it being understood that there is no current flow between heater and cathodes of the tubes in their various functionings. Windings 90 and 91 supply a rectifier system of usual design, 55 comprising rectifier tubes 92, and filter 93. The center tap of filament winding 89 is connected to the negative output side of the filter. Plate operating potential for all tubes is supplied from the positive side of the filter. In order to provide 60 a ballast load on the rectifiers so that the output voltage will not vary excessively upon change of plate current of amplifier tubes 22 and 53, and to provide various fixed and variable biases, a resistor assembly is provided including fixed section 94, variable section 95, and tapped potentiometer section 96. In practice, section 94 may be the 65 field winding of a loud speaker, as also may be one of more of the filter choke windings. Variable resistance section 95 may be used to adjust the system upon changing tubes, and for average tubes, 70 section 95 may be adjusted to approximately half its maximum value. The tapped section 96 is provided with a variable tap 97 connected to the conductor 74, for determining the bias on the amplifier tubes as dynamic multipliers with very 75 weak or no signal; variable taps 98 and 99 for

determining the voltage at which tubes 48 and 47 commence to operate as limiters; fixed taps 100 and 101 for determining the fixed bias for tubes 53 and 22 for normal amplification, with switch 68 to the right; tap 102 for biasing the control amplifiers 72 and 73; tap 103 for ground and bias reference point and bias for cathodes of all amplifier tubes except 22; and tap 104 at the junction of resistances 96 and 95, for producing a slightly positive bias on cathode of tube 22.

In the operation of Fig. 3, after proper settings have been made, the incoming signals are suitably impressed upon the signal amplifier 22 by transformer 21, and upon the control amplifiers 72 and 73 by transformer 71. Rectifiers 35 and 41 are operated in a manner similar to those in Fig. 1, except that rectification by the stronger channel takes greater precedence over rectification by the relatively weaker channel, since transformer 39 delivers more power than transformer 34. Thus, the rectified output of device 41 delivers current to resistance 84, and places a positive bias upon the cathode of rectifier 35, so that said rectifier cannot rectify until the action of device 41 has been limited by tube 48, and the 25 input signals are sufficiently great to overcome the limited bias due to current flowing through resistance 84. This results in improved action, first by rendering rectifier 35 inoperative until tube 41 has ceased producing further effect, and 30 second by permitting transformer 34 to deliver a very high voltage to the second stage tube 73, for quick starting of the control circuits. In this manner the system differs from that described in connection with Fig. 1 in which substantially 35 independent action of the two channels was provided. It will be understood that further modifications of the invention are readily possible, such as by connecting the return terminal of the secondary of transformer 34 not to the junction of resistances 82 and 84, as in the first case, nor to conductor 74, but at some other point of fixed or variable potential, such as an adjustable tap on resistor assembly 96, or a tap on resistance 84.

As a result of the production of control currents in the resistance network, the biases of tubes 22 and 53 are lowered in accordance with the voltages developed therein, the gain ratios of the signal amplifier stages are increased, and the output volume expanded. In case excessive 50 signals are impressed upon the control channel, limiter 47 operates to hold the biases especially of tubes 53 to the value for which maximum amplification is possible without signal distortion.

Although the arrangements shown pertain to 55 the control of one or more stages of signal amplification, by bias grid control for dynamic multiplication or expansion, it is clear that the invention relates also to control for other purposes, of signal amplifiers for dynamic division or compression, and further is applicable for control of a signal amplifier by plate operating potential variation, control by additional electrodes such as in tetrodes, pentodes, etc., and any combinations thereof, as well as control by electrodynamic methods including automatic control of a potentiometer or a rheostat.

Although only a few of the various forms in which this invention may be embodied have been shown herein, it is to be understood that the 70 invention is not limited to any specific construction, but might be embodied in various forms without departing from the spirit of the invention or the scope of the appended claims.

What is claimed is:

1. A system for producing sound from a sound record comprising in combination with a transducer, a control network, means whereby the voltage drop in said network controls the transmission characteristics of said transducer means for introducing currents into said network from a plurality of channels having different transmission characteristics and means for actuating said channels in accordance with the source of signal current applied to said transducer. 10
2. A system for producing sound from a sound record comprising in combination with an amplifier, a control network, means whereby the current in said network controls the amplification factor of said amplifier, means for introducing currents into said network from a plurality of channels having different transmission characteristics and means for actuating said channels in accordance with the source of signal current applied to said amplifier. 15
3. A system for producing sound from a sound record comprising in combination with a space discharge amplifier, a plurality of resistance networks adapted to control the amplification characteristics of said amplifier, individual channels for actuating each of said networks and means for actuating said channels in accordance with the input signal to said amplifier. 20
4. A system for producing sound from a sound record comprising in combination with a space discharge amplifier, a plurality of resistance networks associated therewith, means whereby the voltage drops in each of said networks controls the amplification ratio of said amplifier and means for applying currents to said networks in accordance with the input signal current to said amplifier, the currents applied to the various networks having different characteristics with respect to said input signal current. 25
5. A system for producing sound from a sound record comprising in combination with a space discharge amplifier, a resistance network adapted to control the amplification ratio of said amplifier in accordance with the potential drop therein, means for passing a rectified current through said network including a pair of control channels actuated in accordance with the input signal strength, one of said channels being adapted to produce a greater voltage drop in said network than the other of said channels for a given input signal strength and means for limiting the control of said first channel whereby the control exercised by said second channel predominates at high signal strength. 30
6. A system for producing sound from a sound record comprising in combination with a space discharge amplifier, a resistance network included in the control circuit of said amplifier, means for passing a rectified current through said network including a pair of control channels, the first channel producing a greater response for a given signal volume than the second channel when the signal volume is low, and means for limiting the response of said first channel so that the second channel predominates at high signal strengths. 35
7. A system for producing sound from a sound record comprising in combination with a space discharge amplifier, a resistance network included in the grid return of said amplifier, means for passing a rectified current through said network including a pair of control channels, the first channel producing a greater response for a given signal volume than the second channel when the signal volume is low; and means for 40
- limiting the response of said first channel so that the second channel predominates at high signal strengths. 45
8. A system for producing sound from a sound record comprising in combination with a space discharge amplifier, a resistance network included in the grid return of said amplifier, means for passing a rectified current through said network including a pair of control channels, the first channel producing a greater response for a given signal volume than the second channel when the signals are low, means for limiting the response of said first channel so that the second channel predominates at high signal strengths, and means to prevent actuation of said first channel in response to signals of undesired frequencies. 50
9. A system for producing sound from a sound record comprising in combination with a space discharge amplifier, a resistance network included in the grid return of said amplifier, means for passing a rectified current through said network including a pair of control channels, the first channel producing a greater response for a given signal than the second channel for low signal strength; means for limiting the response of said first channel so that the second channel predominates at high signal strengths, and a filter network associated with said first channel to prevent actuation thereof in response to signals of undesired frequencies. 55
10. A system for producing sound from a sound record comprising in combination with a space discharge amplifier, means for controlling the amplification ratio thereof comprising a control channel, said control channel being operative in response to signals of desired frequencies but being inoperative in response to signals of undesired frequencies unaccompanied by desired signals. 60
11. A system for producing sound from a sound record comprising in combination with a space discharge amplifier, a control channel for controlling the amplification ratio thereof, said control channel having means associated therewith to prevent actuation thereof in response to high frequency signals, except when said signals are of high intensity or are accompanied by signals of other frequencies. 65
12. A system for producing sound from a sound record, comprising an electron discharge amplifier, two control means operable in accordance with the strength of the input signal for varying the characteristics of said amplifier, one of said control means operating to produce a large change in amplification for predetermined changes in signal strength and having limiting means associated therewith to limit the effectiveness thereof to low signal strength, the other of said control means producing a small change in amplification for said predetermined changes in signal strength, the arrangement being such that said first means predominates at small signal strength and said second means predominates at large signal strength. 70
13. A system for producing sound from a sound record, comprising an electron discharge amplifier having a variable gain ratio and control means comprising a multiple stage amplifier operated in accordance with the indicated signal of said record, means controlled by one of said stages for varying said amplification ratio as a predetermined function of the signal characteristics and means controlled by another of said stages for varying said ratio as a different predetermined function of the signal characteristics. 75

14. A system for producing sound from a sound record, comprising an electron discharge amplifier having a variable gain ratio and control means comprising a multiple stage amplifier operated in accordance with the indicated signal of said record, means controlled by the first of said stages for varying said amplification ratio as a predetermined function of the signal and means controlled by the second of said stages for varying 5 said ratio as a predetermined greater function of the signal and limited means for limiting the action of said second means whereby it is effective only for small signals.
15. A system for producing sound from a sound record comprising an electron discharge amplifier having a variable gain ratio and control means comprising a two stage amplifier operated in accordance with the indicated signal strength of said record, means controlled by the first of said 10 stages for varying said amplification ratio as a predetermined function of the signal strength and means controlled by the second of said stages for varying said ratio as a predetermined greater function of the signal strength, means for limiting 15 the action of each of said control means to a predetermined signal strength and means for rendering one of said control means operative in response to a predetermined range of frequencies 20 only.
16. A system for producing sound from a sound record, comprising a space discharge amplifier having variable amplification characteristics, means for varying said characteristics as a predetermined function of the indicated signal 25 strength of said record when the signal strength is small and means for varying said characteristics as a predetermined smaller function of the signal strength when said signal strength is large, whereby a greater range of amplification is obtained at small signal strength than at large signal strength, and means for limiting the action of 30 said first mentioned control means in accordance with a selected band of frequencies only.
17. A system for producing sound from a sound record, comprising a two stage amplifier, control means for controlling the amplification characteristics of each of said stages, means whereby said control means produces a greater change in amplification of said first stage than of said second stage, means whereby said control means is caused to produce a greater change in amplification factor when the input signal strength is small than when the input signal strength is large, and means for limiting the action of said control means for preventing overload of said 35 amplifiers.
18. A system for producing sound from a sound record, comprising a transducer varied by a plurality of similar automatic controls actuated according to different functions of the transducer input signal characteristics.
19. In a sound reproducing system, a sound record, a pick-up device associated therewith, an amplifier fed by said pick-up device, a loud speaker fed by said amplifier, first and second control circuits fed by said pick-up device for determining the gain ratio of said amplifier, said first control circuit discriminating against weak, high frequency tone currents and having sensitive 40 control action, but having its control action with strong tone currents limited, said second control circuit having no substantial effect with weak signals but exerting a dominant control above the limiting point of said first control circuit.
20. A system for producing sound from a sound record comprising in combination with a space discharge amplifier, means for controlling the amplification ratio thereof comprising a control channel, said control channel being operative in response to signals of desired frequencies and intensities but being inoperative in response to signals of undesired frequencies and intensities unaccompanied by desired signals.
21. A system for producing sound from a sound record, comprising a space discharge amplifier having variable amplification characteristics, means for varying said characteristics as a predetermined function of the indicated low frequency signal strength of said record when said signal strength is small and means for varying 10 said characteristics as a predetermined smaller function of the total input signal strength when said signal strength is large, whereby a greater range of amplification is obtained at small signal 15 strength than at large signal strength.
22. A system for producing sound from a sound record, comprising a transducer the transmission characteristics of which are varied by a plurality of similar automatic controls, each actuated according to the transducer input signal strength, the variations effected by the different controls constituting different functions of the change in signal strength, at least one of said controls unresponsive to signals of certain predetermined 20 frequencies.
23. In a system for reproducing sound from a sound record, an amplifier adapted normally to amplify energy derived from said record, means to render said amplifier inoperative when tones having the frequency and intensity characteristics of scratch tones are present and means to render said amplifier operative when tones of different frequencies or of different intensities are present.
24. The method of reproducing sound from a sound record by means of an amplifying system, which comprises varying the gain ratio of the system in accordance with a plurality of different functions of the change in strength of the signal received from the sound record.
25. The method of modifying the reproduction of a sound record which comprises varying the dynamics of the reproduction exclusively according to weak, low pitch notes for weak signals, and then according to stronger notes without regard to pitch for strong signals.
26. The method of modifying the reproduction of sound from a sound record by means of a reproducing system, which comprises rendering the reproducing system inoperative when weak, high frequency notes are present, and rendering the reproducing system operative when low frequency notes of any intensity or when strong high frequency notes are present, whereby the system is prevented from reproducing scratch tones unaccompanied by signal tones.
27. The method of modifying the reproduction of sound from a sound record by means of an amplifier system, which comprises rendering the amplifier system inoperative when weak, high frequency notes alone are present, varying the gain ratio of the system as a function of the intensity of low frequency notes for weak sound energy value and varying the gain ratio of the system as a function of the intensity of notes of all frequencies for stronger energy values.
28. In a system for use with a sound record, a pick-up device, an amplifier tube fed thereby and having a control electrode, a translating device

fed by said amplifier tube, a control circuit including a biasing impedance for determining the bias on said control electrode and a plurality of limiting devices connected to said biasing impedance and operating with different characteristics.

29. In a system for use with a sound record, a pick-up device, an amplifier tube fed thereby and having a control electrode, a translating device fed by said amplifier tube, a control circuit fed by said pick-up device and including a biasing resistance for determining the bias on said control electrode and a plurality of limiting discharge tubes connected across said biasing re-

sistance and operating at different threshold voltages.

30. In a system for use with a sound record, a pick-up device, a main amplifier fed thereby, a translating device fed by said amplifier, a control channel also fed by said pick-up device and controlling the gain ratio of said amplifier, said control channel comprising a plurality of amplifying devices in cascade, whereby said channel may effectively control said main amplifier while receiving only a small volume of energy from said pick-up device. 5
